(57) **CLAIM**

The ornamental design for a visual indicator for alarm unit, as shown and described.

DESCRIPTION

FIG. 1 is a perspective view of a visual indicator for an alarm unit in accordance with the present invention;
FIG. 2 is front side view thereof;
FIG. 3 is right side view thereof;
FIG. 4 is left side view thereof;
FIG. 5 is rear side view thereof;
FIG. 6 is bottom view thereof; and,
FIG. 7 is top view thereof.

The features shown in broken lines in the various figures are for illustrating environmental structure and form no part of the claimed design.
